UNITED STATES PATENT OFFICE.

AXEL THEODOR RYBERG, OF LANGAA, DENMARK.

KEY-SLOT CUTTER.

1,364,524.

Specification of Letters Patent.

Patented Jan. 4, 1921.

Application filed August 22, 1919. Serial No. 319,109.

To all whom it may concern:

Be it known that I, AXEL THEODOR RYBERG, a subject to the King of Denmark, and resident of Langaa, Denmark, have invented 5 certain new and useful Improvements in Key-Slot Cutters, of which the following is a specification.

Vertical machines of known construction for cutting slots in hubs of different machine elements as fly-wheels, pulleys, toothed 10 wheels and the like, are constructed in such a manner that the cutting chisel holder operates above the work table, a projection from the frame of the machine overhanging 15 the work table being provided to guide the chisel holder. This projection limits the diameter of the work piece to be treated in the machine.

This inconvenience is very perceptible in 20 such places where parts of machines of many different shapes and sizes are to be worked.

The present invention comprises a method 25 to eliminate the above described inconvenience and it consists mainly in the work table being placed at the top of the machine, in such a manner that only the top end of the chisel holder projects through a hole in the work table, while all the other parts of 30 the machine are arranged below. This arrangement gives the advantage of being able to clamp on to the work table wheels of even the greatest dimensions.

One manner of construction of this invention is shown in the accompanying drawings, in which—

Figure 1 is a front view of a vertical cut through the slotting machine,

Fig. 2 is the machine seen from the side 40 and partly in section,

Fig. 3 is a part of the machine in horizontal cut through the line A—A in Fig. 2.

Upon the frame 1 of the machine there is a bearing bracket 2 carrying a horizontal 45 shaft 3, the other end of which rests in a bearing 4 upon the frame, and nearest which it carries a toothed wheel 5 that is in engagement with another toothed wheel 6 upon a shaft 7 in the frame. From the shaft 7 the 50 movement is transferred by means of toothed wheels 8 and 9 to a shaft 10, which carries upon the middle a pinion 11 that is in engagement with a rack 12, connected to the cutting chisel holder 13. Upon the top part 55 of the frame the work table 14 is arranged and in the middle of this table is a hole

through which the cutting chisel holder 13 is directed.

The up and down movement of the rack 12 and with that the holder 13 is brought 60 about through the described toothed gearing by means of two loose pulleys 15 and 16 upon the shaft 3. These pulleys are each in tight connection with the half-parts of a claw coupling 17 and 18, between which a 65 claw coupling part 9 is slidably but not rotatably arranged upon the shaft 3 and can be brought into engagement with either of the claw coupling parts 17 or 18. One of the pulley belts is straight, while the other is 70 crossed, so that the pulleys 15 and 16 will be rotated upon the shaft in relatively opposite directions.

The operation of the claw coupling 19 is 75 effected in the following manner.

By means of an operating bar 20 fulcrumed upon a stud 21 in the bearing bracket 2, the claw coupling 19 is in connection with a shaft 22 passing through the machine. About at the middle this shaft 80 is operated upon by the one arm 23 of an angle lever, the top end of which arm is forked and catches around the shaft 22 between two shoulders 24 and 25. The angle lever turns upon a stud 26 in a fork 27 85 clamped to the frame. The other arm 28 of the angle lever is also forked and catches around a vertical shaft 29 with support against disks 30 and 31 that are spring loaded by means of springs 32 and 33, which 90 are given a suitable tension by means of check-rings 34 and 35. The shaft 29 is guided at the top and bottom in bearings 36 and 37. A fork 38 is attached to the rack 12 and catches around the shaft 29. 95

When the machine is started the rack 12 will be moved upward. The fork 38 will be carried up and reaches the collar 39 and pressing against this causes the shaft 29 to be pressed a little upward, at the same time 100 raising the free end of the angle lever arm 28, thereby causing the other angle lever arm 23 to press against the shoulder 25 and push the shaft 22 to the right in Fig. 1. At the same time the operating bar 20 will be 105 turned upon its stud 21 and thereby force the claw coupling 19 out of engagement with the coupling part 18 and into engagement with the coupling part 17 upon the pulley 15, and this will cause the pulley to turn 110 the shaft 3, but in the opposite direction, carrying the rack 12 downward. When the

rack 12, and with it the chisel holder 13, has wandered the defined distance downward, the fork 38 will reach the collar 40 and press upon it. The shaft 29 will now be carried 5 downward and operating upon the angle lever 28 and the organs 23, 22, 20 the claw coupling 19 is released from its connection with the coupling 17 and is put into engagement with the other coupling 18 upon the 10 pulley 16. The reversing has thus taken place and the rack 12 is moved in the opposite direction and so forth.

The collars 39 and 40 are adjustable in 15 order to be able to vary the movement of the cutting chisel holder 13.

The right end of the shaft 22, Fig. 1, is connected to an operating rod 42, fulcrumed upon a stud 41. This operating rod serves 20 as a starting rod for the operator of the machine.

From Figs. 2 and 3 can be seen how the up- and downward-movement of the rack 12 is transferred to the cutting chisel holder 13. The hub, into which a slot is to be cut, is 25 clamped to the work table 14 and the cutting chisel 43 is clamped into its holder by means of a screw 44, the cutting edge turning downward toward the work table. The chisel 13 cuts during the down stroke and 30 is ineffective during the upward movement. In this manner the strain upon the bolts and clamping irons, which hold the hub to the work table 14, is greatly released. During the chisel's movement away from the work 35 table 14 it is automatically held a suitable distance from the bottom of the slot in order that the cutting edge shall not be injured.

Behind the rack 12 (Fig. 3) is arranged a 40 slide 45 guided in the frame 1 and by face plates 46 and 47 in known manner. This slide 45 is provided at the lower side with two ears 48 and 49, between which the chisel holder 13 is placed, fulcrumed on two pivot screws 50 and 51. At the top the slide carries 45 two more ears, of which the one only, 52, is seen in Fig. 2. This lap carries a pin 53 that holds a leaf spring 54 in tension against the chisel holder 13, pressing this to the bottom of the slide 45. At the back of 50 the rack 12 and cast together with this is a projection 55, which passes through an opening in the back wall 56 of the slide 45, projecting a little out from this. Between the chisel holder 13 and the back 56 of the slide 55 45 a rod 57 is arranged, passing through a hole in the projection 55 and provided on either side of this projection with nuts 58 and 59. The lower end of the rod 57 is carried through a bearing 60 cast in one with the slide 45, and below this bearing the rod 60 is acted upon by a tension spring 61, the tension of which is regulated by a nut 62. The top end of the rod 57 is shaped as a wedge 63 and acts upon a larger, loose wedge 64, which rests against the chisel

holder 13. By moving this rod 57 axially in relation to the chisel holder 13, the wedge 63 will cause the top end of the chisel holder 13 to turn a little to the right in Fig. 2, with the pivot screws 50 and 51 as fulcrum, and this takes place when the cutting chisel is being carried away from the work table 14, in order that the cutting edge of the chisel 43 shall not touch the bottom of the slot that is being cut. 75

Supposing the chisel holder 13 has passed its uppermost position and is now beginning its downward movement. The pinion 11 rotates in the direction indicated by the arrow Fig. 2, and the rack is carried downward. The projection 55 on the rack will press upon the nut 59 and thereby pull the slide 45 and with that the chisel holder 13 down, and the chisel will cut a piece out of the slot. When the lowest position is 80 reached, the reversing is brought about as described earlier, and the pinion 11 will rotate in the direction opposite to that indicated by the arrow, carrying the chisel holder 13 upward. Simultaneously with the reversing the projection 55 will press upon the upper nut 58 and carry the rod 57 a little upward before the slide 45 accompanies, all in accordance with the tension of the spring 61. The wedge 63 on the end of the 85 rod 57 will hereby be removed a little in relation to the wedge 64, and the leaf spring 54 will press the chisel holder 13 a little back (to the right Fig. 2) and in this manner the cutting chisel will not touch the bottom of the slot. 90

By regulating the tension of the spring 61 and the upward movement of the wedge 63 in the proper manner, this retrogressive device for the cutting chisel is exceedingly 105 reliable, which has been proved through thorough experiments.

In order to make it possible in an easy and reliable manner to cut a deeper slot in one end of the hub than in the other end 110 thereof, the work table 14 can be given an inclined position at any angle, which can be controlled by means of an index, of known construction.

Any change of the inclination of the 115 work table 14 is brought about by means of a screw 65, Fig. 2, which can be screwed up against the lower side 70 of the work table 14, and thereby lift it, the table turning on a screw or bolt 66, passing through the 120 frame and two laps 67 and 68, Fig. 1, clamped to the work table. When the desired position is arrived at, the clamping screw 69, Fig. 2, is tightened.

After each working stroke, the work table 125 14 is fed a little way toward the cutting edge of the chisel 43. This feed is effected through a handle 71, attached to a spindle 72, screwed into a tight nut 73, upon the lower side of the table 14. By giving the 130

handle 71 a suitable turn after each stroke, the work table and the work piece clamped to it, is carried toward the cutting chisel 43, and a new chip is cut off at the bottom of 5 the slot.

I have shown an embodiment of my invention, but it is clear that changes may be made therein without departing from the spirit thereof as defined in the appended 10 claims.

What I claim is:

1. A machine for cutting key slots and the like including a tool biased to a position out of operative relation to the work, means for 15 vibrating said tool, and means actuated by said tool vibrating means for shifting the tool at the beginning of its working stroke and prior to any working movement on the part of the tool into operative engagement 20 with the work.

2. A machine for cutting key slots and the like including a tool biased to a position out of operative contact with the work, a slide carrying said tool, actuating means for said 25 slide, said actuating means being movable relatively to the slide at the ends of the movement of the tool, and means carried by the slide and acting on the tool for moving the same into operative engagement with 30 the work, said last mentioned means being directly coupled to the tool vibrating means whereby such vibrating means will initially act upon the last mentioned means and will subsequently act upon the slide to cause 35 movement of the same together with the tool.

3. A machine for cutting key slots and the like comprising a tool biased to a position out of operative contact with the work, vi- 40 brating means for actuating the tool, and coacting wedge elements shifted by said

actuating means initially to move the tool at the beginning of the working stroke of said tool into contact with the work.

4. A machine for cutting key slots and the like comprising a reciprocating slide, a tool holder pivoted therein, spring means acting on the tool holder to normally swing the tool out of operative contact with the work, relatively movable wedge elements 50 carried by said slide, tension means for one of said wedge elements, and reciprocating means for the slide acting upon said tensioned wedge elements to initially shift the same relatively to the companion wedge ele- 55 ment prior to imparting movement to the slide.

5. A machine for cutting key slots includ- 60 ing a slide, a holder pivotally mounted on said slide, a cutter carried by the holder, means for reciprocating the slide and the holder as a unit, a spring urging the holder in one direction to disengage the cutter from the work, coacting wedge elements mounted in the slide and limiting such movement 65 of the holder to maintain the cutter in operative engagement with the work during the reciprocatory movement of the holder in one direction, means actuated by a part of the reciprocating means at the start of 70 the movement of the holder in an opposite direction to shift one of the wedge elements and permit of the pivotal movement of said holder, and the retrocession of the cutter to an inoperative position with respect to the 75 work.

In testimony whereof I affix my signature in presence of two witnesses.

AXEL THEODOR RYBERG.
